Harry W. Brown.
ATTORNEY.

UNITED STATES PATENT OFFICE.

FRANK V. MOREN, OF WEST SPRINGFIELD, MASSACHUSETTS.

TAILOR'S TRY-ON CLASP.

1,419,165.

Specification of Letters Patent. Patented June 13, 1922.

Application filed March 9, 1922. Serial No. 542,337.

To all whom it may concern:

Be it known that I, FRANK V. MOREN, a subject to the King of Sweden, residing at West Springfield, county of Hampden, State 5 of Massachusetts, have invented certain new and useful Improvements in Tailors' Try-On Clasps, of which the following is a specification.

This invention relates to improvements in 10 tailors' try-on clasp for the purpose of temporarily holding or retaining the meeting edges of a garment as a coat in position while the same is being fitted to the person.

Heretofore it has been a common practice 15 for the tailor to use pins for temporarily holding the edges of a garment in position as a coat, while being fitted. This practice is objectionable particularly where the material or the cloth is comparatively thick 20 as when an overcoat is being fitted.

The present invention comprises broadly 25 a pair of spring actuated pins or prongs that are normally drawn toward each other by means of contraction springs and means operating and separating the prongs when the clasp is used for spacing the distance between the prongs so that it may be applied.

Referring to the drawings:

30 Fig. 1 is an elevational view showing the clasp in place for temporarily holding the meeting edges of a garment together while being fitted.

Fig. 2 is a side elevational view of the 35 clasp, the full lines showing the closed position and the dotted lines the open position when it is applied.

Fig. 3 is a top plan view of Fig. 2 and Figs. 4 and 5 are details of the clasp.

40 Referring to the drawings in detail:

1 and 2 designate parallel bars or side members which are connected together by the bottom plate 3 forming in effect a U- or channel shaped member. 4 designates a pin 45 which extends transversely of the members 1 and 2. 5 and 6 are thumb pieces that are pivotally connected to the members 1 and 2 by means of the pins 7 and 8 which pass through the ears 9 and 10. These ears are 50 integral parts of the thumb pieces 5 and 6 and are located on opposite sides of the members 1 and 2 as shown. These thumb pieces extend in opposite directions from the pivots. Their inner ends are connected to 55 the coiled springs 11 and 12 which springs

are connected to the pin 4. The normal effect of these springs is to draw the thumb pieces 5 and 6 inward as shown in full lines in Fig. 2 and against the opposite ends of the pieces 1 and 2. The opposite ends of 60 the thumb pieces 5 and 6 are broadened or have a flattened surface 13 and are engaged by the thumb and finger of the operator when the clasp is used by opening the members 5 and 6 in applying the clasp to the 65 garment. Attached to the inner ends of these members are the sharpened prongs 14. These prongs or needle like members as shown in plan view in Fig. 3 are U-shaped and are securely attached to the pieces 5 and 70 6 by means of the turned over part 15. These sharp points therefore move with the pieces 5 and 6.

The device is used as follows:

When the garment is being tried on the 75 meeting edges 16 and 17 are placed in the correct position or fitting desired. The operator then opens or spaces the prongs 14 as shown in the dotted line position in Fig. 2 and places the clasp on the edges of the 80 garment. The springs 11 and 12 retract causing the sharp prongs to enter the cloth or fabric and retain the edges of the garment in the position desired, permitting the fitter to mark the cloth in the usual manner with chalk or other means when the garment is fitted. The pieces 5 and 6 are now opened and the prongs removed from the garment the ends of the members 1 and 2 serve as stops for the inward movement of 90 the thumb pieces.

It is of course understood that the clasp may be made in different sizes for different thicknesses of material. Some of the advantages are that it eliminates the use of 95 pins which are not reliable when the material is thick, also it increases the efficiency of the tailor as they are quickly applied and removed and effectively retain the edges in the positions desired without any displacement.

What I claim is:

1. In a tailor's try-on clasp, the combination, of a channel shaped member, a pin located therein, pointed members pivotally connected to the channel shaped member and each normally having a bearing on its respective end of the channel shaped member for limiting its inward movement, springs connecting the pin and pointed 105 110

members for drawing the pivotal members toward each other and against the ends of the channel shaped member but permitting their separation when the clasp is applied to 5 the meeting edges of a garment, as described.

2. In a clasp construction, the combination, of a channel shaped member, a pin connecting the opposite side members, springs connected to the pin and extending in opposite 10 directions, members pivotally connected to the channel shaped member and to which the outer ends of the springs are connected, the ends of the channel shaped member serving as stops to limit the inward movement 15 of the pivotal members, said pivotal mem-

bers having outwardly extending portions for receiving the thumb and finger members.

3. In a tailor's try-on clasp, the combination, of a channel shaped member, members formed with ears pivotally connected to the 20 opposite ends of the channel shaped member, springs connected to the pivotally connected members for normally drawing the same against the ends of the channel shaped member, the inner ends of the pivotal members having U-shaped sharpened points for engaging the meeting edges of a garment, whereby when the points are separated the 25 device may be applied.

FRANK V. MOREN.
